UNITED STATES PATENT OFFICE.

WILLIAM HARRY HAYTER, OF SOUTH NORWOOD, LONDON, ENGLAND.

CAM-LEVER.

1,281,000.

Specification of Letters Patent.

Patented Oct. 8, 1918.

Application filed May 13, 1918. Serial No. 234,147.

To all whom it may concern:

Be it known that I, WILLIAM HARRY HAYTER, subject of George V, King of Great Britain and Ireland, and residing at 27 Birchanger road, South Norwood, in the county of London, England, have invented certain new and useful Improvements in Cam-Levers, of which the following is a specification.

10 This application is a continuation in part of application Serial No. 148,810, filed February 15th, 1917.

This invention relates to improvements in and connected with levers having a cam-head which, when in operative position, exerts pressure at two points, one on each side of the fulcrum. According to this invention, the lever is so designed and mounted that, during the time it is being forced home, the rear or heel-portion of the cam-surface exerts pressure at one of said points and moves the lever in an endwise direction so as to cause the front or toe-portion of the cam-surface to slide over and exerts pressure at the other of said points.

In the accompanying drawings,

Figure 1 is a side elevation of a lever constructed in accordance with this invention.

Fig. 2 illustrates how the lever may be employed in fastening members together, a portion of the lever-support and a portion of one of the members having been broken away in order to more clearly illustrate how the lever operates.

35 Figs. 3 and 4 are fragmentary views illustrative of two further methods of using the lever.

Figs. 5 and 6 show modifications of the lever in respect of its slot.

40 Fig. 7 shows in side elevation a form of "multiple" lever constructed in accordance with this invention.

Fig. 8 shows a further modification of the lever.

45 Like letters of reference refer to like parts throughout the drawings.

Referring to the drawings, A is the lever which is mounted, by means of a slot a' therein, on a pivot b in a slot c formed in 50 one end of a pin or support c' (hereinafter termed the "tie") the other end of which is provided with a head c'' , Fig. 2. The pivot is a fixture. The longer arm of the lever is in the form of a handle, preferably provided with a depression a^2 for the purpose

of accommodating one of the operator's fingers, and is also provided with a heel a^3 . The shorter arm of the lever is in the form of a toe a^4 . The slot c is of such a depth as to allow the lever to be swung over on its 60 pivot.

Dealing now with the method, illustrated in Fig. 2, of fastening the three members d , e , f , together, the members d and e are provided with holes d' and e' , respectively, 65 through which the tie c' , with the lever in the position shown in broken lines in Fig. 2, is passed up to its head c'' . The lever is then swung down so that its longer arm lies flat against the member e , as shown in full 70 lines. During the downward movement of the longer arm, the heel a^3 engages one side of the hole e' thereby causing the lever to move from right to left; as seen in the figure, and the toe a^4 to ride up on the opposite 75 side of the hole. During this forcing or snapping home of the lever the members become drawn tightly together. It will be seen that when the lever is at rest its arms press upon the member e at two points—one 80

on each side of the pivot b . The pressure at these two points is transmitted direct to the pivot and, as these pressures oppose or, as may be arranged, balance one another, the lever is caused to automatically maintain 85 or lock itself in position and is prevented from accidentally rising and permitting the members to separate.

In order to cause the lever to snap tightly against the member e , it is preferable to so 90 fashion that portion of the surface of the heel that is remote from the toe that it meets the flat under surface of the lever at or about a right angle, so that just prior to the lever completing its movement toward the member the heel sinks suddenly into the pin c' and the long arm of the lever snaps with a 95 rapid movement against the member e . In order to release the lever an outward pull must be applied to its longer arm.

Referring to Fig. 3, the heel a^3 and toe 100 a^4 bear on the bottom of the slot c and on the member e respectively, while in Fig. 4 the heel and toe bear on the member e and bottom of the slot c respectively. In both 105 cases the downward movement of the lever forces the member e home. It will be obvious that instead of utilizing the bottom of the slot c , for the heel in the one case or the toe in the other case, to work against, 110

any other suitable form of abutment or surface which is stationary relatively to the tie *c'* may be employed for the same purpose.

When the lever is in the position shown in 5 broken lines in Fig. 2, the member *e* can be given a preliminary push home by swinging the lever to the left and pressing its arcuate portion *a'* (lying opposite the portion extending from the heel *a*³ to the toe *a*⁴) upon 10 the adjacent edge portion of the hole *e'*.

The slot *a'* may be arranged at an inclination, as illustrated in Fig. 5, and it may be open-ended, as illustrated in Fig. 6.

In some cases, according to this invention, 15 the pivot is fixed in the lever and works in a slot provided in the tie *c'*. If this slot is horizontal or approximately so it may be open-ended so that the pivot can be readily introduced into it.

20 If a single throw of the lever is found to be insufficient to produce the required pressure, *e. g.*, when compressing a bale of soft goods, increased pressure can be obtained in stages by swinging the lever up into the 25 position shown in broken lines in Fig. 2, threading a washer or washers over it, and then bringing it down again so that the heel and toe of the lever act upon the washer or washers instead of upon the member *e*, until 30 the required pressure is obtained.

An alternative method of obtaining increased pressure is to employ what I may term a "multiple" lever, that is, two or more levers constructed as above described but 35 each having a different throw and mounted on a single pivot. An example of such an arrangement is illustrated in Fig. 7. This figure shows what may be termed a "triple" lever, *i. e.*, three levers mounted on a single 40 pivot. The broken lines show the levers in non-operative position, while the full lines show them in the position they occupy after they have been forced down into contact 45 with the pressure-member. In using these levers they are turned down in the order of their throw commencing with the lever having the least throw; that is, lever No. 1 is first turned down, then lever No. 2, and finally lever No. 3. The lever to be last 50 turned down may be provided with a catch *a'* or other device adapted to engage the levers previously turned down so as to fasten the several levers together.

The surfaces against which the heel and 55 toe of the lever operate instead of being plane, as illustrated, may be rounded.

In some cases, as some sort of a safeguard against unauthorized opening of the lever, the long arm of the latter is shortened back 60 to about the length of the short arm, as illustrated in Fig. 8, and is provided with a hole *a'* to receive a removable pin (not shown);

by inserting this pin into the hole *a'* and pulling it upward the lever can be opened.

Having thus described my invention, what 65 I claim as new and desire to secure by Letters Patent is:

1. A cam-lever adapted to be pivotally mounted in a slotted element so as to bear with the heel and toe of its cam face on an 70 additional element on opposite sides of said slotted element, said cam-lever being provided with a slot to receive the pivot pin and allow longitudinal movement of said lever thereon, and said slot being disposed at an 75 angle to the cam face, in order that the cam face may act on said additional element on one side of said slotted element to force the lever longitudinally on said pivot pin until the cam face engages said additional element on the other side of said slotted element. 80

2. A cam-lever adapted to be mounted for longitudinal and pivotal movement in a slotted element so as to bear, in normal position, 85 with the heel and toe of its cam face on an additional element on opposite sides of said slotted element in order that the cam face may act on said additional element to force the lever longitudinally until the cam face 90 engages said additional element on two sides of said slotted element.

3. A cam-lever adapted to be mounted for longitudinal and pivotal movement in a slotted element so as to bear, in normal position, 95 with the heel and toe of its cam face on relatively substantially fixed surfaces on opposite sides of its pivotal point in normal position, a portion of said cam face in operation 100 engaging one of said fixed surfaces on one side of the pivotal point and forcing the cam-lever as a whole longitudinally until another portion of said cam face engages the other of said fixed surfaces on the other side of said pivotal point. 105

4. A plurality of cam levers all mounted on a common pivot pin and adapted to be arranged in a slotted element so that each lever may bear in sequence on an additional element adjacent to said slotted element and so that the respective cam faces may engage relatively substantially fixed surfaces on opposite sides of their pivotal points, said cam levers being provided with slots to receive the pivot pin and allow longitudinal movement of said levers thereon, and said slots being disposed at an angle to the respective cam faces, the curvatures of said cam faces differing successively in order that the desired pressure may be easily obtained by forcing said cam levers into normal position in regular order. 110

In witness I have hereunto set my hand.
WILLIAM HARRY HAYTER.
